UNITED STATES PATENT OFFICE

2,035,000

COMBINED SINK AND DRAIN

Eulalie Swain, Midland, Tex.

Application June 14, 1935, Serial No. 26,668

2 Claims. (Cl. 4—189)

The object of my invention is to provide a novel combined sink and drain having separate drain pipes for the drain and for the sink, and having the rim of the drain and of the sink level and continuous and set level in the frame but having the bottoms slightly inclined toward the discharge opening, and having a novel arrangement of ribs for the bottom of the drain, and having the drain and sink combined in one unit and cast integrally and with rounded corners broadly curved to facilitate cleaning. I attain these and other objects of my invention by the means illustrated in the accompanying drawing, in which—

15 Figure 1 is a top plan view of my combined sink and drain;

Fig. 2 is a longitudinal section through same with a slightly modified drain opening;

Fig. 3 is a perspective view of the invention with 20 a modified ribbing for the drain; and

Fig. 4 is a side elevation showing the preferred arrangement of the drain pipes.

Like numerals designate like parts in each of the several views.

25 Referring to the accompanying drawing, there is illustrated a sink 1, an integral drain 2, having an integral and level rim 3 and an intervening level rim 4. The sink is provided with the discharge openings 5, and the drain is provided with 30 the discharge openings 6, or the conventional large drain channel 5' for sink 1 and a conventional type of large drain opening 6' for drain 2. The bottoms of the sink and drain incline slightly 35 from all points to the point of discharge, but the rims are level throughout, as illustrated.

The sink drain 5 opens into the drain pipe 7 and the drain opening 6 opens into the drain pipe 8, which is connected at 10 with the sink drain 7 at a point above the trap 8, as shown in Fig. 4. I may provide the diagonally disposed ribs 11 integral with the bottom of the drain 2, as shown in Fig. 3; or I may provide a parallel arrangement of ribs 12, as shown in Fig. 1, the latter being my preferred construction as it provides a more uniform support for the dishes placed in the drain.

As shown in Fig. 1, both the sink and the drain are provided with broadly curved corners 50 which permit of easy cleaning of the sink and

drain. One of the advantages of this new type of sink is that it can be built in a cabinet and supported by its level rim, and it also can be constructed at a reasonable cost within the price range of the average purchaser. It will be noted 5 that as the drain has a separate drain pipe it can take care of an unlimited amount of rinsing water without in the least interfering with the sink proper.

An important feature of the invention is that 10 as the rim of the sink and drain are continuous and level throughout, a cabinet top can be built perfectly level and the sink and drain mounted in same. This construction also increases the possibilities of carrying out attractive decorative 15 schemes in connection with the cabinet and the sink.

While I prefer to connect the drains 7 and 9 as shown in Fig. 4, it is within the contemplation of my invention to provide a separate trap for 20 the drain pipe 6, if for plumbing reasons such construction is desired. It is contemplated that this sink may be used with a swinging type of faucet, which may be swung either over the sink or the drain, as desired. Or a rubber hose and 25 spray may be connected with a conventional faucet, if that type of faucet is already provided.

It will be noted that the drain pipes of the sink and the drain are both located at adjacent ends of the sink and drain, whereby a short pipe 30 9 will connect the ends as shown, at 10 where pipe 9 enters pipe 7.

What I claim is:

1. A main sink and an integral relatively shallow auxiliary drain sink, each having a drain 35 opening and pipe positioned near adjacent ends of the drain and sink, said pipes being connected at a point above the trap.

2. A main sink and an integral relatively shallow auxiliary drain sink, each having a drain 40 pipe near adjacent ends of the drain and sink, the drain having spaced upstanding ribs, and having the rims of the sink and of the drain continuous and level throughout, the connecting 45 portion of the sink and drain being a partition and making in effect separate units of the sink and drain and being on a level with the outside rims.

EULALIE SWAIN,
